UNITED STATES PATENT OFFICE.

GUSTAVE E. VILLARET, OF LEONIA, NEW JERSEY.

DESIGN FOR A CHANDELIER.

Application filed September 22, 1928. Serial No. 28,242. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for a Chandelier, of which the following is a specification, reference being had to the accompany-

ing drawing, forming a part thereof, in which

Fig. 1 is a view slightly in perspective, showing my new design; and

Fig. 2 is a plan view showing contour.

I claim:

The ornamental design for a chandelier, as shown.
